UNITED STATES PATENT OFFICE.

GEORGE W. MAREMBECK, OF PHILADELPHIA, PENNSYLVANIA.

AIR-HEATING FURNACE.

SPECIFICATION forming part of Letters Patent No. 290,902, dated December 25, 1883.

Application filed June 11, 1883. (No model.)

To all whom it may concern:

Be it known that I, GEORGE W. MAREM-
BECK, a citizen of the United States, and a
resident of Philadelphia, Pennsylvania, have
5 invented certain Improvements in Air-Heating
Furnaces, of which the following is a speci-
fication.

The main object of my invention is to so
construct an air-heating furnace as to insure
10 extended air-heating surfaces without unduly
increasing the height of the structure.

The invention also comprises minor features
of construction with the view of controlling
the combustion and readily cleaning the flues.

15 In the accompanying drawings, Figure 1 is
a longitudinal section of my improved furnace;
Fig. 2, a transverse section on the line 1 2;
Fig. 3, a transverse section on the line 3 4,
and Fig. 4 a sectional plan on the line 5 6.

20 A is the outer casing of the furnace, inclos-
ing the air-heating chamber B. This casing
may be of sheet metal or of brick, and is fur-
nished with the usual openings, a, for the en-
trance of cold air, and with branches b for the
25 escape of the heated air.

Within the chamber B is suitably support-
ed the cylindrical casing D of the combustion-
chamber F, and within the latter is a cylin-
30 drical casing, G, the chamber H within which
receives a supply of cold air from a chamber,
K, at the rear of the furnace, and discharges
the heated air into a chamber, J, at the front
of the same, the air being conveyed from the
35 latter chamber by suitable pipes. The annu-
lar combustion-chamber communicates with
the fire-place M, and with an exit-pipe, N,
extending longitudinally through the chamber
H, and communicating with an adjacent chim-
40 ney, longitudinal deflecting-plates d in the
chamber F causing the products of combus-
tion to take a circuitous course in their pas-
sage from the fire-place to the outlet, so as to
be brought into contact with all portions of
45 the casings D and G. The chamber H is con-
tracted above the fire-place, in order to permit
the free flow of the products of combustion
into the chamber F, and to provide for di-
rect draft. The deflecting-plates d have near
50 their front ends valves f, on opening which
the products of combustion are at liberty to

pass directly upward, so as to enter the pipe
N. The front end of the pipe N passes through
the casing of the chamber J, and has a de-
tachable cap, g, on removing which access may
be had to the pipe for the removal of soot there-
from, and the front plate, P, of the heater has
55 doors h in line with the plates d, for a similar
purpose, and also for permitting access to the
valves f when it becomes necessary to operate
the latter for the purpose of controlling the 60
draft.

It will be noticed that in the above heater
two volumes of air are being simultaneously
heated—one by contact with the outer casing
65 of the combustion-chamber, and the other by
contact with the inner casing of the same and
with the exit-pipe N.

In a furnace constructed as shown heating-
surface may be extended indefinitely by in-
creasing the length of the structure without in-
creasing its height or width—an advantageous
70 feature, as the apartments in which heaters
are usually located are frequently low and
narrow, but are generally so long that longi-
tudinal extension of the structure is not ob-
jectionable. Moreover, economy is insured, as
75 the same front and rear castings can be used
in building heaters of different sizes.

The contracted portion of the casing G of
the combustion-chamber may be provided with
80 blocks or slabs of fire-brick to prevent warp-
ing of the same by the intense heat to which
it is subjected.

I claim as my invention—

1. The combination of the fire-place, the in-
ner and outer heating-chambers, H and B, the
annular combustion-chamber F between the
85 two, the exit-pipe N, and longitudinal deflect-
ing-plates d in said combustion-chamber, as set
forth.

2. The combination of the outer casing, A,
and the end plates inclosing the heating-cham-
ber B, with the fire-place M, the casing D, in-
closing the chamber F, and the casing G, in-
90 closing the heating-chamber H, said casing G
having above the fire-place an offset forming a
combustion-chamber communicating with the
front end of the chamber F, as set forth.

3. The combination of the fire-place, the in-
ner and outer heating-chambers, H and B, the
100

exit-pipe N, and the annular combustion-chamber F, having deflecting-plates *d*, with valves *f*, as set forth.

4. The combination of the fire-place, the inner and outer heating-chambers, H and B, the annular combustion-chamber F, having deflecting-plates *d*, and the front plate, P, having doors *h* in line with said plates, as set forth.

In testimony whereof I have signed my name to this specification in the presence of two subscribing witnesses.

GEO. W. MAREMBECK.
